The ornamental design for a grate for a smokeless grill, as shown and described.

DESCRIPTION

FIG. 1 is a front, left, top perspective view of a grate for a smokeless grill showing my design therefor;
FIG. 2 is a top plan view thereof;
FIG. 3 is a bottom plan view thereof;
FIG. 4 is a left side elevational view thereof;
FIG. 5 is a right side elevational view thereof;
FIG. 6 is a front elevational view thereof, the rear elevational view being a mirror image thereof;
FIG. 7 is a cross-sectional view of FIG. 2, taken along line 7-7 thereof;
FIG. 8 is a front, left, top perspective view of a second embodiment of a grate for a smokeless grill;
FIG. 9 is a top plan view of the second embodiment;
FIG. 10 is a bottom plan view of the second embodiment;
FIG. 11 is a left side elevational view of the second embodiment;
FIG. 12 is a right side elevational view of the second embodiment;
FIG. 13 is a front elevational view of the second embodiment, the rear elevational view being a mirror image thereof; and,
FIG. 14 is a cross-sectional view of FIG. 9, taken along line 14-14 thereof.

The broken lines shown in the drawings are for illustrative purposes only and form no part of the claimed design.
